(73) Assignee: **IdeaStream Consumer Products LLC**, Parma, OH (US)

CLAIM

(**) Term: **14 Years**

The ornamental design for a storage device for optical media such as CDs, as shown and described.

(21) Appl. No.: **29/181,739**

DESCRIPTION

(22) Filed: **May 16, 2003**

A portion of the disclosure of this patent document contains material to which a claim for copyright is made. The copyright owner has no objection to the facsimile reproduction of the patent document or the patent disclosure, as it appears in the Patent and Trademark Office patent file or records, but reserves all other copyrights whatsoever.

(51) **LOC (8) Cl. 06-04**

FIG. 1 is a perspective view of a storage device for optical media such as CDs embodying our new design;

(52) **U.S. Cl. D6/632; D6/634; D6/635**

FIG. 2 is a right side view thereof;

(58) **Field of Classification Search D3/201,**

FIG. 3 is a left side view thereof;

D3/218; D6/407, 626–635; 206/307.1, 308.1,

FIG. 4 is a top plan view thereof;

206/308.2, 308.3, 309, 311, 312, 387.11,

FIG. 5 is a bottom plan view thereof;

206/387.12, 387.15; 369/37, 75.2, 291; 379/355

FIG. 6 is a front view thereof; and,

See application file for complete search history.

FIG. 7 is a rear view thereof.

(56) **References Cited**

The areas of texture shown in FIGS. 1, 4 and 5 are understood to extend across the entire surface.

U.S. PATENT DOCUMENTS

The outermost broken lines showing the logo, hinges and clasp throughout the views, represent the unclaimed boundaries of the design. The boundary lines themselves, form no part of the claim. The broken lines within the boundaries, along with the broken line showing a chain, illustrate the portions of the design that form no part of the claim.
